UNITED STATES PATENT OFFICE.

JAMES HOLLINGSWORTH CLEGG, OF LISCARD, WALLASEY, ENGLAND.

APPARATUS FOR SCALING, CLEANING, OR OTHERWISE ACTING UPON SURFACES.

1,323,964.

Specification of Letters Patent.

Patented Dec. 2, 1919.

Application filed July 31, 1916. Serial No. 112,381.

To all whom it may concern:

Be it known that I, JAMES HOLLINGSWORTH CLEGG, a subject of the King of England, and resident of Liscard, Wallasey, in the county of Chester, England, have invented new and useful Improvements in Apparatus for Scaling, Cleaning, or Otherwise Acting Upon Surfaces, of which the following is a specification.

10 This invention has reference to apparatus for operating upon surfaces, such as "scaling" and cleaning the surfaces of steam generators and other metal surfaces; cleaning or burnishing surfaces, and otherwise similarly operating upon the surfaces of metal, or other materials; and the invention has for its object to improve apparatus of this kind, and more particularly that type of such apparatus in which the operative tool 15 or instrument is mounted on and worked by a flexible shaft, driven by an electric motor.

The apparatus according to this invention is illustrated in the accompanying drawings of which Figure 1 is a view showing the 20 motor part of the apparatus and its containing box. Fig. 2 is an outside elevation of the end of the flexible shaft, at which the tools are carried; and Figs. 3 and 4 are elevations showing one form of tool proper; and Figs. 5 and 6 show other two forms of 25 tools. Fig. 7 represents a central sectional view of the mechanism shown in Fig. 2, to more clearly illustrate the detailed construction of said mechanism.

30 Referring now to the drawings, 1 is the electric motor, and 2 the starting and controlling appliance, of which 3 is the handle; 35 4 is the body of the box in which these parts are contained; and 5 is the lid. The handle 40 3 projects out through one end of the box, so that when the box is closed the motor can be started or stopped or regulated as desired. 6 is the screw threaded end of the electric motor shaft; and to this end the 45 rigid terminal 8 of the flexible driving shaft 7 is directly fixed; this terminal being hollow and internally threaded, and adapted to receive the shaft end 6.

The flexible continuous bearing tube of 50 the flexible shaft 7 is designated 10, and it consists of intercoiled and interlocking reverse channel shaped spiral wires; a type of tube largely used for conducting steam and water; and one end of this bearing tube 55 has fixed on it a rigid sleeve bearing 11 having flanges 12, which is fixed and held in a

tubular bearing 13, fixed in one end of the box 4; and the rigid terminal 8 of the internal flexible shaft 7 passes through this bearing sleeve 11.

60 The other end of the tube 10 is provided with a rigid tubular part 15, which in each end is provided with ball bearings 17; and the flexible shaft is provided at this part with a rigid spindle 16 which passes through 65 and revolves within this tube, and is supported by these ball bearings; and this spindle 16 carries the tools proper; that is tools are fixed on its end which is threaded and has a shoulder as shown, and the tools 70 are fixed in position by a nut or the like.

It will be seen by reference to Fig. 7, that the tubular part, or member 15, is provided at each end with a recess 15', which forms 75 seats for the caps or plugs 19, one of which forms the bearing for the spindle 16, while the other cap receives the rigid tube or guide 18, which is secured to the flexible bearing tube 10.

The rigid tube part 18 is soldered or otherwise fixed on to the end of the flexible bearing tube 10, and the inner end of the bearing tube 15 is mounted and fixed on this part 18.

It will be noted that the coupling part 8 80 of the flexible shaft comes close up to the inner end of the bearing or bush 11, so that the flexible driving shaft is supported close to its end.

85 The flexible bearing tube 10 is slightly 90 larger in diameter internally, than the external diameter of the flexible shaft 7; and it is found that with this clearance, in the presence of a lubricant, the apparatus works better, and less power relatively is used for 95 operating the tool, and getting a given effect.

90 The scaling or cleaning tool in the form 100 shown in Figs. 3 and 4, consists of a carrier comprised of two disks 20 spaced apart, and fixed to, and driven by the driving shaft end 16 which passes through them; the one disk being detachably fastened with other by screw bolts and nuts, or the like, to the other disk. Between these disks the loosely 105 mounted toothed cutters or operative tools 21 are placed; so that when the tool is revolved, these cutters can fly outward centrifugally; and they may have play in other directions in some cases.

110 There may be two, three or more of these cutters or devices in each complete tool.

- Another form of tool, shown in Fig. 5 is suitable for scaling or clearing tubes; the cutters or operative devices 21 in the case being arranged in the carrier 20 one in front of the other. If desired the tools proper 21 may be in the form of an ellipse with serrated or studded cutting or active edges or points. The tools are loose as in the former case, and act similarly as above described.
- 10 A conical tool 22 is shown provided on the carrier 20, and can be used for any purpose to which it is suited.

In another case the operative part of the tool may consist of flexible flails 23, of wire 15 or other material—depending on the work the tool has to perform—secured suitably in the carrier 20.

What is claimed is:—

An apparatus of the character described, 20 consisting of a motor, a starting and con-

trolling means therefor, a flexible bearing tube mounted contiguous to the motor, a flexible shaft supported in said flexible bearing tube and having one end connected with the shaft of the motor, a spindle terminal formed on said shaft, a rotary tool attached to said spindle terminal, a sleeve inclosing said spindle, a cap fitting one end of said sleeve, and forming a bearing for said spindle, a cap fitting the other end of 30 said sleeve, a tubular guide secured in said cap, and ball bearings disposed between said sleeve and spindle.

In testimony whereof I have signed my name to this specification in the presence of 35 two subscribing witnesses.

JAMES HOLLINGSWORTH CLEGG.

Witnesses.
